UNITED STATES PATENT OFFICE.

MAX RACHLIN, OF NEW YORK, N. Y., ASSIGNOR TO APEX GUTTER HANGER CORPORATION, OF NEW YORK, N. Y., A DOMESTIC CORPORATION.

GUTTER HANGER.

Application filed April 13, 1925. Serial No. 22,623.

To all whom it may concern:

Be it known that I, MAX RACHLIN, a citizen of Russia, and resident of the city of New York, in the county of Kings and State 5 of New York, have invented certain new and useful Improvements in Gutter Hangers, of which the following is a specification.

The present invention relates to improvements in gutter-hangers, and has for its 10 main object to provide a device of this type which may be applied to ordinary gutters as well as to ogee gutters.

Another object of the invention is to produce a simple gutter-hanger of the type mentioned, provided with very simple means which serves to support the gutter in such a manner as to preclude any danger of the latter becoming detached from the body of the hanger.

With these and other objects in view, which will more fully appear as the nature of the invention is better understood, the same consists in the combination, arrangement and construction of parts hereinafter 25 described, pointed out in the appended claims and illustrated in the accompanying drawings, it being understood that many changes may be made in the size and proportion of the several parts and details of construction within the scope of the appended 30 claims, without departing from the spirit or sacrificing any of the advantages of the invention.

One of the many possible embodiments of 35 the invention is illustrated in the accompanying drawings, in which:—

Figure 1 is a side elevation of a gutter-hanger constructed in accordance with the present invention; Fig. 2 is a top plan view 40 of one section of the said hanger in its developed state; Fig. 3 is a side elevation of the hanger applied to an ordinary gutter, the latter being shown in section; and Figs. 4 and 5 are similar elevations, the hanger 45 being applied to ogee gutters.

The gutter-hanger comprises a rigid body portion 10, preferably a channel bar, adapted to extend transversely between the upper edges of the gutter. On one end of this bar 50 is formed an arched portion 11, that is designed to be bent around the bead of a gutter. The free end of the arched portion terminates in a sharp point 12, and in alignment with this point there is formed in the 55 arched portion a longitudinal slot 13. The

opposite end of the body portion 10 is bent upwardly, as shown at 14, thence outwardly, as indicated at 15, and thence downwardly, as indicated at 16. The lower end of the downwardly extending portion 16 is bent inwardly, as indicated at 17, and this inwardly bent portion is provided with a sharp pointed free end 18, for a purpose herein-after to be described.

To the central portion of the bar 10 is 60 attached a roof strap 19, to be secured in any suitable manner to the roof.

For supporting the gutter in proper relation to the roof of the building, a plurality of these hangers is used, they being spaced 70 apart a suitable distance.

In Fig. 3 of the drawings, the hanger is shown applied to an ordinary roof gutter, denoted by the numeral 20. The outer edge of this gutter is provided with a bead 21, 75 while its inner edge 22, adjacent the wall of the building, is plain. In mounting the hanger on the gutter, the free end of the arched portion 11 is inserted into the bead, its point 12 being brought into engagement 80 with the inner face of the bead. When then the arched portion 11 is bent around into snug engagement with the bead of the gutter, the point 12 forms a dent 23 in the bead, the said dent being forced into the slot 13, as 85 clearly shown in Fig. 3 of the drawings. The upwardly extending portion 14 on the opposite end of the bar 10 is then engaged with the inner face of the plain edge 22 of the gutter, the outwardly extending portion 90 15 bridging over the said free edge. The downwardly extending portion 16 is then brought flush against the outer face of the plain edge of the gutter and, finally, the sharp point 18 forced into the body of the 95 gutter, so as to form a dent 24 therein. Inasmuch as both ends of the hanger extend into dents in the gutter body, the hanger cannot become detached from the gutter. As a matter of fact, the hanger cannot even 100 move on the gutter in the direction of the longitudinal axis of the latter.

In Fig. 4 of the drawings an ogee gutter 25 is illustrated. One of the longitudinal edges of this gutter is provided with a 105 square bead 26, while its other longitudinal edge, denoted by the numeral 27, is plain. In attaching the hanger to this gutter, the arched portion 11 of the hanger is bent to correspond to the square bead of the gutter, 110

the sharp point 12 of the arched portion being forced into the bead, to form a dent 28 therein. Otherwise the hanger is attached to the gutter in the manner described 5 in connection with Fig. 3 of the drawings.

The ogee gutter 29 illustrated in Fig. 5 of the drawings differs from the one described in connection with Fig. 4 of the drawings in that it is provided with a round bead 10 30. The hanger is fastened to this gutter in the manner described in connection with the gutter shown in Fig. 3 of the drawings.

From the foregoing it appears that the hanger may be applied to ordinary gutters 15 and also to ogee gutters, without necessitating any changes whatever in the construction thereof.

What I claim is:—

1. A gutter-hanger, including a rigid portion adapted to extend transversely between the upper edges of the gutter, an arched portion at one end of said rigid portion designed to fit around the bead of the gutter,

and an upwardly and downwardly bent portion on the other end of said rigid portion 25 adapted to engage the plain edge of the gutter, both ends of said hanger having sharp points to be forced into the gutter, said arched portion being provided with a longitudinal slot in alignment with the 30 sharp point thereof, whereby said last-mentioned sharp point is disposed within said slot when said arched portion is bent around said bead.

2. In a gutter hanger, a bracing strip 35 having its ends adapted to be snugly engaged with the upper terminal portion of an ogee gutter, said end portions of said bracing strip being provided with slots and terminating in pointed tabs, which are adapted 40 to be punched through the material of the gutter and inserted within said slots.

Signed at New York, in the county of New York, and State of New York, this 10th day of April, A. D. 1925.

MAX RACHLIN.
